SYNCHROS

CROSS-REFERENCES TO RELATED APPLICATIONS

This application is a continuation-in-part of U.S. Pat. application Ser. No. 820,584 now abandoned entitled "Synchros" invented by Willis Guy Wing, George Edward March Baker and Rodney Frank Smith, filed Apr. 30, 1969 and assigned to the present assignee.

This invention relates generally to synchros and has for its object to provide a combined synchro-torquing device.

The two main types of synchros are torque synchros and control synchros. In the case of a torque synchro system a torque transmitter and a torque receiver are provided and movement of the transmitter rotor is repeated synchronously by movement of the receiver rotor. This system is not power amplifying and inherently has large transmitting errors. Accordingly, there is a limit to the use of torque synchros as torque transmitting devices and as an accurate servo system.

When receiver torques are required of an order greater than that which can be satisfactorily handled by a torque synchro, a control synchro system is used. Here a control transmitter and a control receiver are used but in addition an electronic amplifier and servomotor are required. Good transmission accuracy is, however, achieved with such a system. The cost of this system is greater than that of a torque synchro system and, equally important, the system is physically larger. The latter consideration is of particular concern in the case of navigational systems, for example, such as an inertial platform. There is an ever increasing requirement for navigational and other equipment to be made as small as possible in order that maximum utilization of space in an aircraft, for example, can be obtained. The accurate transmission of data from gimbals to an electronic unit of an inertial platform necessitates the use of the control synchro system and the addition to this of torque motors on the gimbal system must further increase the over-all physical size of the gyro enclosure, together with the cost of the complete platform.

According to the present invention a synchro-torquing device comprises a control transmitter synchro, a control receiver synchro connected to receive a data output signal from the transmitter synchro, and means for supplying a torquing current to the receiver synchro, electrical means being provided to obviate the effect of the torquing current on the data signal output from the receiver.

Thus there is provided a control synchro system from which can be obtained current-controlled torque outputs from either transmitter or receiver without having to employ a separate torque motor. The electrical means serve to eliminate from the output signal of the receiver synchro any component signal, referred to hereinafter as the "error signal", resulting from the torquing current. Thus the output signal is the unimpaired data signal from the transmitter.

Preferably, the electrical means is a transformer the primary winding of which is connected in series with the receiver synchro rotor winding. The primary winding may be shunted by a resistance. It is necessary to design the transformer so that the voltage appearing across the secondary winding cancels out the voltage appearing across the rotor of the receiver synchro due to the torquing current applied.

It has been found on investigation that due to practical limitations, even though the transformer design is carried out to agree with theory, elimination of error voltage by the transformer secondary voltage is not exact, the degree of unbalance between the two rising with increase of torquing current. Also, the required value of shunt resistance is very critical in determining the compensating performance of the system and unbalance becomes less linear with increase of torquing current. It will be appreciated that a constant unbalance can be accommodated by suitable setting up procedures in use of the device, but a varying unbalance cannot be accepted.

By increasing the required value of the resistance shunting the transformer primary the balance condition can be made less sensitive to changes in this resistance and degree of unbalance will not increase so sharply with rise of torquing current. This increase of required resistance can be effected by increasing the Q value of the transformer primary winding while at the same time decreasing its impedance; a small air gap in the transformer circuit will produce these effects. Decrease in the receiver short circuit rotor impedance will also help reduce the criticality of balance.

It can be shown that the problem of non-linearity of unbalance can be eased by making the Q value looking into the receiver rotor equal to unity. Another factor which adversely affects the ability of the system to cancel the error signal at all times is the change in carrier frequency of the torquing current. It can be shown that in order to reduce the effect of frequency variation the Q value looking into the receiver rotor should be low compared with unity, which is at variance with the requirements associated with the problem of non-linearity of unbalance. A compromise between the two has to be reached. Ideally a low iron loss in the transformer is also required.

Introduction of a preset air gap into the transformer as discussed above will ensure a more stable inductance. Attainment of very stable inductance and also waveforms of similar shape for cancelling may be achieved by using a pair of synchros as the transformer, ideally constructed in the same way as the synchros used for the actual data transmission.

It will be seen that there is an over-all requirement for a low impedance control receiver synchro for which unconventional winding methods may be employed.

As an alternative to the use of a transformer, the electrical means may comprise a capacitive-resistive model to back off the error signal, in a manner to be more fully explained later.

A synchro-torquing system in accordance with the invention will now be described in greater detail, by way of example, with reference to the accompanying drawings, in which:

FIG. 1 is a diagrammatic representation of the system,

FIG. 2 shows the equivalent electrical circuit of FIG. 1, and

FIGS. 3 and 4 are graphs of angular error against torquing current for the system under different conditions.

The capacitive-resistive model embodiment of the invention will be explained in greater detail later with reference to the drawings in which:

FIG. 5 is a diagrammatic representation of the capacitive-resistive model embodiment of the system; and

FIG. 6 shows the equivalent electrical circuit of FIG. 5.

The synchro-torquing system comprises a control transmitter synchro (CX) 1 and a control receiver synchro (CT) 2 connected to receive a data output signal from the transmitter synchro. Each of the synchros 1 and 2 comprises a wound stator and a wound rotor and, in use, the stator of the transmitter is energized by an alternation voltage. Upon a change in the energizing voltage movement of the transmitter rotor takes place which is repeated synchronously by movement of the rotor of the receiver synchro 2. A torquing current I is applied to the receiver synchro 2 and in order to prevent this from impairing the data output signal from the synchro by introducing an error signal, a transformer 3 is connected in series with its rotor winding.

The primary winding 4 of the transformer 3 is connected in series with the receiver synchro rotor winding and is shunted by a resistance R . The torquing current I is applied through the transformer primary winding 4 and the data output signal is taken out via the secondary winding 5.

In FIG. 2 the pair of synchros 1, 2 is represented as a source of alternating voltage e and the primary winding 4 of the transformer 3 is represented as an inductance L_T in series with a resistance R_T and is current driven from a source E_1 . The data voltage e is required unimpaired from the secondary winding 5 of the transformer 3 as an output data signal E_o .

Z_s represents the equivalent impedance of the pair of synchros 1 and 2 looking into the receiver synchro rotor and $Z_s = R_s + j\omega L_s$. The transformer, with a turns ratio of N_2/N_1 has a primary impedance of $Z_T = R_T + j\omega L_T$. Writing Krichhoff's equations for the network gives:

$$\begin{aligned} E_1 - V &= i_1 R \\ E_1 - V &= i_2 Z_T \end{aligned} \quad (1)$$

$$V - e = i_1 Z_s + i_2 Z_s$$

Also

$$E_o = V - N_2/N_1 \cdot V_p = V - N_2/N_1 \cdot j\omega L_T \cdot i_2 \quad (2)$$

Solving equation (1) for V and i_2 and substituting in equation (2) gives

$$E_o = [E_1 (R \cdot N_2/N_1 \cdot j\omega L_T - Z_s \cdot Z_T - Z_s R)] / [-(RZ_T + Z_s \cdot Z_T + Z_s R)] - [e(RZ_T + N_2/N_1 \cdot Rj\omega L_T)] / [-(RZ_T + Z_s \cdot Z_T + RZ_s)] \quad (5)$$

In order to make $E_o = +e$ we need $Z_s \cdot Z_T + RZ_s = R \cdot N_2/N_1 \cdot jL_T$

Equating real parts requires that:

$$R = R_T (Q_s \cdot Q_T - 1),$$

and equating imaginary parts requires that:

$$L_T/L_s = (R + R_T) / (R \cdot N_2/N_1 - R_s)$$

Combining these requirements gives:

$$\begin{aligned} L_T/L_s &= (N_2/N_1) \cdot (Q_T/Q_s) \cdot (Q_s^2 + 1) / (Q_s \cdot Q_T - 1) \\ &= (1/K) \cdot (N_2/N_1) \end{aligned}$$

where

$$Q_T = Q_s / [Q_s^2 - K(Q_s^2 + 1)]$$

Thus, choice of a value of K , $[(Q_s^2 / (Q_s^2 + 1))]$ for a given Q_s (i.e., for a given CT-CX pair), will set a value for Q_T . The actual values of L_T and R_T will be governed by size, power, iron saturation considerations in the transformer 3. The turns ratio N_2/N_1 may be computed from the formula $N_2/N_1 = K \cdot L_T/L_s$, and the shunt resistance R from $R = R_T (Q_s \cdot Q_T - 1)$.

In an experimental system, two 26 volt standard cased synchros were used and the impedance looking into the receiver rotor of the pair of synchros was $268 + j160$ ohms, this agreeing well with the theoretical value calculated by considering the equivalent T-circuits of the synchros. $Q_s = 0.597$ and a transformer with $Q_T = 4.56$ and $R_T = 12.4$ ohms was designed and wound on a bobbin having a laminated radio metal core. This design theoretically requires a shunt resistance R of 21.5 ohms

If there is still some component of the voltage due to the torquing current across the receiver synchro rotor, this will appear as an angular error between the two synchros. Angular error was plotted against torquing current for varying values of R and the results are as illustrated in FIG. 3. It will be seen from FIG. 3 that the value of R required for balance is extremely critical; small deviations of R from the balance condition will greatly increase the angular error per unit torquing current. It will also be noted that the plots become less

linear with increase of torquing current. It can be shown if $[\delta\theta/\delta I]_R = X$ is the rate of change of angular error with torquing current at constant R , then $[\delta X/\delta R]_{R=0}$, which is the rate change of X with R at the balance condition, is equal to $-K_2/(R/Z_s + R^2/Z_s Z_T)$, where K_2 is the voltage gradient in the synchro. Thus to remove the criticality of the shunt resistance R , the Q value of the primary winding 4 of the transformer 3 can be increased while at the same time decreasing its impedance; a small air gap in the transformer will produce these effects. In view of these theoretical considerations a new transformer was designed with $Q_T = 7.4$ and $R_T = 22.8$ ohms, giving a required shunt resistance R of 79 ohms. This entailed an increase of Z_T from 55 to 172. Thus R was increased by a factor of 4 and Z_T by a factor of 3 giving a good reduction of $\delta X/\delta R$ where $X = 0$.

Again, angular error was plotted against torquing current and it will be seen from FIG. 4 that the same type of curve as obtained previously resulted, but compared with the previous curves there is shown a marked decrease in the rate of change of $\delta\theta/\delta I$ with R , as expected theoretically. Even larger increases in R , while keeping Z_s and Z_T small, should give even less criticality of R .

With regard to the non-linearity of the curves obtained, particularly with increase of torquing current, it was found that this was due to the heating effect of the torquing current and it can be shown that in order to reduce this effect the value of Q_s should be unity. As to the variation in performance of the synchro-torquing system with carrier frequency, it can also be shown that the value of Q_s should be less than unity. This being at variance with the requirement for Q_s to be unity in con-

nection with linearity and clearly, a compromise has to be reached.

The torque performance of the system is given by the equation

$$T = I/2\omega \delta E/\delta\theta 10^7 \text{ dynes}$$

where $\delta E/\delta\theta$ is the voltage gradient inside the synchro, ω is the frequency of operation, and I is the torquing current. Thus T is proportional to I for a given system. Practical measurement, using a size 13 slave type transmitter synchro and size 08 standard cased receiver synchro with equivalent impedance of $Z_s = 227 + j309$, gave a torque/current characteristic linear up to 6 gm-cm at 0.06 gm-cm per mA after which saturation of the receiver synchro began. Use of a commercially-available synchro pair with equivalent impedance of $Z_s = 173 + j167$ should allow this torque to be increased to 8 gm-cm before saturation, lower impedances giving even higher torques.

Referring now to FIG. 5, in which like reference numerals refer to like components with respect to FIG. 1, the capacitive-resistive embodiment of the invention is illustrated. Torquing current I is applied to the receiver synchro rotor winding via a resistor R_1 connected in series therewith. Resistors R_2 and R_3 , which are connected together in series, are coupled in shunt across the resistor R_1 . A capacitor C_1 is connected across the resistor R_2 . The inputs to an amplifier 14 are connected to receive the signals appearing across the resistor R_3 . The amplifier 14 is a difference amplifier of a conventional type wherein the signal at the inverting input 15 is reduced by a factor of $\frac{1}{2}$ before it is subtracted from the signal at the non-inverting input 16. The amplifier 14 provides an output signal $E_o/2$ representative of one-half the data output signal from the synchro 2 in a manner to be explained with respect to FIG. 6.

In FIG. 6, the torquing current I provided by a high impedance source E_1 , produces a voltage e_i across the receiver synchro rotor winding where:

$$e_i = i R_s [1 + j\omega \tau_s]$$

with

$$\tau_s = L_s/R_s. \quad (3)$$

If the resistors R_2 and R_3 are chosen to have values very large compared to the resistor R_1 , then the voltage, e , appearing across the inputs to the amplifier 14 may be expressed as:

$$e = i R_1 [R_3/(R_1 + R_3)] [1 + j R_2 \omega C_1] / [(1 + j)(R_2 R_3)/(R_2 + R_3) \omega C_1] \quad (4)$$

or

$$e = i R_1 k (1 + j\omega \tau_1) / (1 + j\omega \tau_2) \quad (5)$$

where

$$R_1 C_1 = \tau_1, k = R_3/(R_1 + R_3), \tau_2 = k \tau_1.$$

Equation (5) may be rewritten as

$$e = i R_1 k [(1 + \omega^2 \tau_1 \tau_2) / (1 + \omega^2 \tau_2^2) + j\omega (\tau_1 - \tau_2) / (1 + \omega^2 \tau_2^2)]. \quad (6)$$

It may now be appreciated that by comparing equation (6) with equation (3), the voltage e will be equal to e_i when:

$$k R_1 [(1 + \omega^2 \tau_1 \tau_2) / (1 + \omega^2 \tau_2^2)] = R_s, \text{ and} \quad (7)$$

$$k R_1 [(\tau_1 - \tau_2) / (1 + \omega^2 \tau_2^2)] = R_s \tau_s \quad (8)$$

Combining equations (7) and (8)

$$\tau_s = (\tau_1 - \tau_2) / (1 + \omega^2 \tau_2^2) = R_s \tau_s \quad (9)$$

which relationship must hold in order that $e = e_i$.

When the condition of equation (9) is satisfied and the voltage e equals the voltage e_i , the voltage V at the input 16 of the amplifier 14 is:

$$V = E_o + e_i \quad (10)$$

where E_o is the data signal output from the receiver synchro 2 and e_i is the voltage from the synchro 2 resulting from the torquing current I .

By virtue of the resistors R_1 and R_2 , the voltage V also appears at the input 15 of the amplifier 14. Since the voltage e appears across the inputs of the amplifier 14 and $e = e_i$, the composite voltage at the input 15 with respect to the input 16 is:

$$E_o + 2 e_i \quad (11)$$

Since the inverting input 15 has an associated gain of one-half and the non-inverting input 16 has an associated gain of unity, the output of the difference amplifier 14 is:

$$E_o + e_i - \frac{1}{2} (E_o + 2 e_i) = E_o/2.$$

Thus, a voltage equal to one-half the receiver data signal output signal is provided at the output of the amplifier 14 obviated of the effect of the torquing current I . The gain of the output stages of the amplifier 14 may be adjusted to compensate for the factor of one-half thereby providing a signal equal to E_o as desired.

In the example given with respect of FIG. 1, $Q_s = 0.597$ and the frequency $\omega = 400$ Hz. For convenience of calculation let $Q_s = 0.6$ and $\omega = 2500$ radians per second (approximately 400 Hertz). In addition, let $k = 5$ which is a value found to be proper for the present embodiment. For equation (9) and based on the example given, there are two possible sets of values for τ_1 and τ_2 , namely:

$$\tau_1 = 2.322 \times 10^{-3} \text{ seconds},$$

$$\tau_2 = 0.464 \times 10^{-3} \text{ seconds, or}$$

$$\tau_1 = 3.445 \times 10^{-4} \text{ seconds,}$$

$$\tau_2 = 0.689 \times 10^{-4} \text{ seconds, where}$$

$$R_1 = 1.520 R_s \text{ for the first set, and}$$

$$R_1 = 4.485 R_s \text{ for the second set.}$$

The circuit of the capacitive-resistive embodiment of the invention is less sensitive to frequency changes utilizing the second set of values and would ordinarily be preferred.

It may be appreciated that the capacitive-resistive embodiment of the invention may be preferred to the transformer embodiment described with respect to FIG. 1 for purposes where the size and weight of the transformer required may be objectionable.

A synchro torquing system in accordance with the invention is particularly advantageous when employed in an inertial platform, which is normally required to be as small as possible. The system avoids the need for separate torque motors positioned on the gimbals, with a consequential saving in cost as well as space. It has been found that a synchro torquing system in accordance with the invention is capable of handling torques of the order required in inertial platforms. Examples of inertial platforms in which the invention may be employed are well known in the art.

While the invention has been described in its preferred embodiment, it is to be understood that the words which have been used are words of description rather than limitation and that changes may be made within the purview of the appended claims without departing from the true scope and spirit of the invention.

We claim:

1. A synchro torquing device comprising a control transmitter synchro, a control receiver synchro connected to receive a data output signal from the transmitter synchro, means for supplying a torquing current to the receiver synchro, and electrical means operable to obviate the effect of torquing current on the data signal output from the receiver.

2. A synchro torquing device according to claim 1, wherein the electrical means is a transformer the primary winding of which is connected in series with the receiver synchro rotor winding.

3. A synchro torquing device comprising a control

transmitter synchro, a control receiver synchro connected to receive a data output signal from the transmitter synchro, means for supplying a torquing current to the receiver synchro, a transformer the primary winding of which is connected in series with the receiver synchro rotor winding, and a resistance connected to shunt said primary winding, the transformer being operable to obviate the effect of torquing current on the data signal output from the receiver.

4. A synchro torquing device comprising a control transmitter synchro, a control receiver synchro connected to receive a data output signal from the transmitter synchro, means for supplying a torquing current to the receiver synchro, and a transformer the primary winding of which is connected in series with the receiver synchro rotor winding, the transformer circuit having an air gap therein thus increasing the Q value and decreasing the impedance of the primary winding, the transformer operable to obviate the effect of torquing current on the data signal output from the receiver.

5. A synchro torquing device according to claim 1, wherein the electrical means comprises resistor-capacitor network means.

6. A synchro torquing device according to claim 1, wherein the electrical means comprises resistor-capacitor network means coupled with the receiver synchro rotor winding.
